CLAIM

The ornamental design for a flamingo lawn ornament, as shown and described.

DESCRIPTION

FIG. 1 is a top perspective view of a flamingo lawn ornament, shown in an opened configuration and without leg supports;

FIG. 2 is a top plan view of the flamingo lawn ornament of FIG. 1;

FIG. 3 is a front side elevation view of the flamingo lawn ornament of FIG. 1;

FIG. 4 is a left side elevation view of the flamingo lawn ornament of FIG. 1;

FIG. 5 is a right side elevation view of the flamingo lawn ornament of FIG. 1;

FIG. 6 is a rear side elevation view of the flamingo lawn ornament of FIG. 1;

FIG. 7 is a bottom view of the flamingo lawn ornament of FIG. 1;

FIG. 8 a bottom perspective view of the flamingo lawn ornament of FIG. 1;

FIG. 9 is a top perspective view of the flamingo lawn ornament of FIG. 1, but shown with leg supports;

FIG. 10 is a top plan view of the flamingo lawn ornament of FIG. 9;

FIG. 11 is a front side elevation view of the flamingo lawn ornament of FIG. 9;

FIG. 12 is a left side elevation view of the flamingo lawn ornament of FIG. 9;

FIG. 13 is a right side elevation view of the flamingo lawn ornament of FIG. 9;

FIG. 14 is a rear side elevation view of the flamingo lawn ornament of FIG. 9;

FIG. 15 is a bottom view of the flamingo lawn ornament of FIG. 9;

FIG. 16 a bottom perspective view of the flamingo lawn ornament of FIG. 9;

FIG. 17 is a front perspective view of the flamingo lawn ornament of FIG. 1, but shown in a closed configuration;

FIG. 18 is a top plan view of the flamingo lawn ornament of FIG. 17;

FIG. 19 is a right side elevation view of the flamingo lawn ornament of FIG. 17;

FIG. 20 is a front side elevation view of the flamingo lawn ornament of FIG. 17;

(Continued)

FIG. 21 is a rear side elevation view of the flamingo lawn ornament of FIG. 17;
FIG. 22 is a left side elevation view of the flamingo lawn ornament of FIG. 17;
FIG. 23 is a bottom view of the flamingo lawn ornament of FIG. 17;
FIG. 24 a rear perspective view of the flamingo lawn ornament of FIG. 17;
FIG. 25 is a front perspective view of the flamingo lawn ornament of FIG. 17, but shown with leg supports in a position of use;
FIG. 26 is a top plan view of the flamingo lawn ornament of FIG. 25;
FIG. 27 is a right side elevation view of the flamingo lawn ornament of FIG. 25;
FIG. 28 is a front side elevation view of the flamingo lawn ornament of FIG. 25;
FIG. 29 is a rear side elevation view of the flamingo lawn ornament of FIG. 25;
FIG. 30 is a left side elevation view of the flamingo lawn ornament of FIG. 25;
FIG. 31 is a bottom view of the flamingo lawn ornament of FIG. 25; and,

FIG. 32 a rear perspective view of the flamingo lawn ornament of FIG. 25.
